(57) **CLAIM**

The ornamental design for a cutlery storage device, as shown and described.

DESCRIPTION

FIG. 1 is a top perspective view of the cutlery storage device showing my new design.

FIG. 2 is a top view thereof.

FIG. 3 is a bottom view thereof.

FIG. 4 is a first side view thereof.

FIG. 5 is a second side view thereof.

FIG. 6 is a third side view thereof; and,

FIG. 7 is a forth side view thereof.

The broken lines in the drawings illustrate portions of the cutlery storage device which form no part of the claimed design.
